UNITED STATES PATENT OFFICE.

HENRY A. CORDRAY, OF LOS ANGELES, CALIFORNIA.

TABLE.

1,295,438.

Specification of Letters Patent.

Patented Feb. 25, 1919.

Application filed October 22, 1917. Serial No. 197,766.

To all whom it may concern:

Be it known that I, HENRY A. CORDRAY, a citizen of the United States, residing at Los Angeles, in the county of Los Angeles 5 and State of California, have invented a new and useful Table, of which the following is a specification.

This invention relates to a table and particularly pertains to a combined table and 10 cabinet.

It is the object of this invention to provide a table embodying foldable or hinged extension panels and a movable false top adapted to be raised and lowered on rock- 15 ing of the panels whereby articles on the false top may be quickly concealed on folding the panels.

Another object is to provide a simple and effective means for actuating the false top 20 without the use of weights or springs and by direct connection to the foldable panels.

Another object is to provide a table of the above character which can be manufactured at small cost, and which consists of 25 few parts dependable in their operation and not liable to get out of order.

Other objects will appear hereinafter.

The invention is illustrated in the accompanying drawings, in which:

30 Figure 1 is a view in vertical section and elevation showing the table in its open or extended position with the false top elevated.

Fig. 2 is a view in elevation of the upper 35 portion of the table showing the extension or foldable top in closed position.

Fig. 3 is a detail section illustrating the manner of connecting the foldable panels to the false top.

40 Fig. 4 is a detail in perspective of the flexible member for connecting the false top and panels.

Fig. 5 is an enlarged section as seen on the line 5—5 of Fig. 2.

45 In carrying out my invention in its preferred embodiment as here shown, I provide a rectangular box frame 6 open at its top and fitted with an outwardly projecting ledge 7 forming the projecting edges of the 50 table top. The bottom of the frame is preferably open and covered with a screen 8, but it may be sealed if desired. Supporting legs 9 carry the frame and are detachably connected thereto so that they may be removed and packed in the box frame for shipment. In order to provide a substantial con-

nection between the frame and legs the latter are rabbeted at one corner to receive the corners of the frame to form a shoulder 10 on which the frame seats. Screws 11 or 60 other suitable fastenings are employed to attach the legs to the frame.

The essence of the invention resides in the table top construction which comprises a false top panel 12 movable vertically in 65 the frame, a pair of side foldable panels 13 hinged at 14 to the opposite side ledges of the frame, and connections whereby the top panel is raised and lowered by swinging the panels. The connections between the 70 panels and false top consist of chains 15 or other suitable flexible members. A pair of the chains are connected to hook brackets 16 on the underside of the opposite edges of the false top and extend upwardly 75 through notches 17. The outer portions of the chains pass through channels 18 on the ledges and their terminals are secured to hook plates 19 in channels 20 on the folding panels. The folding panels are designed 80 to be extended horizontally on opposite sides of the frame in which position they may be supported in any desired manner, hinged brackets 21 being here shown as employed for this purpose. The chains are of 85 such length that when the panels 13 are disposed in a horizontal position as shown in Fig. 1 the false top 12 will be disposed flush with the upper surface of the ledge 18 and the panels 13.

When the panels 13 are disposed in their folded position as shown in Fig. 2 the chains will depend vertically adjacent the inner side walls of the box frame thus positioning the false top in a suspended position below 95 the folded top, thus forming a compartment in which articles may be stored and concealed. As a means for providing space for tall articles, such as bottles, the false top may be fitted with a depending well 22.

100 In the operation of the invention the brackets 21 are swung outwardly and the panels 13 are swung upwardly and outwardly to their horizontal position on the brackets 21. The upward movement of the 105 panels acts through the chains to elevate the false top and the articles carried thereon into its uppermost position to form with the panels a continuous table top.

110 When it is desired to conceal articles within the compartment, they are disposed on the false top whereupon the folding side

panels are swung to their inward position as shown in Fig. 2 thus causing the false top to move to its lowermost position. The folding panels are of such width that when 5 disposed in their folded position they will completely cover the box frame and its contents. The abutting edges of the panels may be rabbeted to form overlapping tongues 23 and the panel carrying the uppermost 10 tongue may be engaged by a latch 24 of any suitable description whereby the panels may be locked in their folded position.

The box frame may be utilized as a packing box in shipment in which event the 15 false top may be fastened in its lowermost position by dowel pins 25 or the like which are inserted through the side panels of the box frame into engagement with the edges of the false top. Any other suitable means 20 may be employed for retaining the false top in its lowermost position. In shipping the legs may be removed and packed within the compartment formed in the box frame.

As a means for permitting the top panels 25 to be swung downwardly as indicated by the dotted lines *a* in Fig. 1 while the false top is in its uppermost position, the under side of the hingedly connected edges of the panels and ledge are beveled at an angle of 30 45 degrees as indicated at 26.

While I have shown and described a specific embodiment of my invention, it is manifest that various changes may be made in the details of construction without departing from the spirit of the invention as set forth in the appended claims.

The chains 15 are of such length that when the top panels 13 are in their closed position the false top 12 will rest upon the 40 shoulders 10 as shown in Fig. 5, and the chains will hang suspended in their compartment in a slack condition. In order to effect sufficient vertical movement of the false top to dispose it flush with the upper 45 edge of the ledge 7 when the panels 13 are extended, it is necessary to attach the chains 15 to the panels sufficiently far from the hinged connections of the latter so as to take up the slack in the chains and draw 50 the latter taut when the panels are swung to their extended position.

I claim:

1. In a table, a box frame, a pair of hinged top panels thereon adapted to depend therefrom, a false top therein, and

connections between said panels and false top whereby swinging said panels will effect vertical movement of said false top to dispose the false top in alignment with the top panels when the latter are horizontal 60 and adapted to permit movement of the top panels to their dependent positions.

2. In a table, a box frame, a false top vertically movable therein, a pair of panels hinged on the sides of said frame to depend 65 therefrom, adapted to be swung inwardly to cover the frame and false top, and flexible connections between said panels and false tops whereby the latter will be suspended from the panels when the latter are 70 in their folded position and by means of which the false top can be raised by swinging the hinged panels upwardly and outwardly.

3. In a table, a box frame, a false top 75 vertically movable therein, a pair of panels hinged on the sides of said frame to depend therefrom, adapted to be swung inwardly to cover the frame and false top, flexible connections between said panels and false 80 top whereby the latter will be suspended from the panels when the latter are in their folded position and by means of which the false top can be raised by swinging the hinged panels upwardly and outwardly, and 85 means whereby said panels may be supported horizontally in their extended position.

4. In a table, a box frame, an outwardly projecting ledge on the upper edges thereof, vertically swinging panels hinged to the outer edges of the ledge on the sides of the frame to depend therefrom, said panels and the ledges carrying same being formed with aligned channels adjacent their ends, a false 90 top vertically movable in said frame, flexible members connected to the edges of said false top and connected to the hinged panels to support the false top and adapted to extend in the channels on the ledge and panel 100 when the latter are in their horizontal position, said connections serving as a means for raising and lowering the false top on swinging the hinged panel, and foldable means on the box frame for supporting the 105 top panels in a horizontal position in alignment with the ledge and false top when the latter is in its uppermost position.

HENRY A. CORDRAY.
